UNITED STATES PATENT OFFICE.

BERNARD J. DOWD AND ANTHONY UTZ, OF HARTFORD, CONNECTICUT, ASSIGNEES TO
ROYAL TYPEWRITER COMPANY INC., OF NEW YORK, N. Y., A CORPORATION OF
NEW YORK.

TYPEWRITING MACHINE.

Application filed July 3, 1922. Serial No. 572,395.

To all whom it may concern:

Be it known that we, BERNARD J. Dowd, a citizen of the United States, and a resident of Hartford, in the county of Hartford and

5 State of Connecticut, and ANTHONY Utz, a citizen of the United States, and a resident of Hartford, in the county of Hartford and State of Connecticut, have invented certain new and useful Improvements in
10 Typewriting Machines, of which the following is a specification.

This invention relates generally to type bar actions for typewriting machines and has for its main object a construction where-
15 by a uniform touch of the keys comprising the keyboard coupled with greater simplicity than has heretofore existed in the construction of the train of connections composing the type bar action, is obtained.

20 In the accompanying drawings, the invention is disclosed in several concrete and preferred forms in which:

Fig. 1 is a vertical longitudinal sectional view through the well-known "Royal" typewriting machine with parts omitted for the sake of clearness, the parts shown being the elements comprising the type bar action of the machine in their relation to the platen.

25 Fig. 2 is a horizontal sectional view on the plane of line 2—2 of Fig. 1.

Fig. 3 is a view similar to Fig. 1 showing a modified form of the invention.

30 1 indicates a platen, 2 is a type bar segment extending transversely of the machine and curved in a vertical direction and 3 indicates a series of typebars pivotally connected at 4 to said type bar segment and normally occupying a forwardly recumbent

35 position in engagement with head rest 5. 6 indicates a series of key levers pivotally supported on shaft 7; and 8 indicates a universal bar. Connected to the heel of each type bar is a draw link 9, the other end

40 of which is connected to front link 10 pivotally supported in the framework; and extending between each front link and its complementary key lever is a vertical link 11. Spring 12 restores the key lever to its
45 uppermost position after it has been depressed. 13 is a universal bar link extending between the universal bar and the train of connections including the key lever and type bar. 14 is a type bar operating spring

surrounding each universal bar link, one 55 end of which is connected to some element of the type bar action and the other end of which is anchored extraneously thereof as on the framework or on adjustable member 15. It will be understood that there is only 60 one universal bar and one member 15 but that there is a series of each of the other elements.

It will be apparent that, owing to the curvature of the type bar segment, the type 65 bar operating springs, if anchored at points in the same transverse plane on member 15, will be unequally extended; that is, those springs that are furthest away from the center, transversely, of member 15, will be 70 more extended than the others.

In Patent No. 1,084,547 of January 13, 1914, the universal bar link and the type 75 bar operating spring are secured to the draw link by means of a fixed pendant so that the difference in the tension of the springs is not compensated for. These pendants, however, occupy a certain amount of space and, create congestion owing to the confinement of the intermediate connections in 80 a limited space. In Patent No. 1,390,708 of Sept. 13, 1921 a certain new and advantageous construction is disclosed whereby the pendants of Patent No. 1,084,547 are done away with, but no means are shown to compensate for the difference in extension of the springs. Also, since in Patent No. 1,390,708 the universal bar link and type bar 85 operating springs are connected to the heel of the type bar at different points, the movement of the type bar will produce unequal movements of the link and spring which has certain disadvantages.

These difficulties are obviated in the construction shown in Figs. 1 and 2 of the present application in that one of the links in the train of connections, in this case the universal bar link, is provided with an integral looped portion 16 intermediate its ends in which the end of spring 14 is secured. In 95 addition to this, anchorage 15 is of a peculiar construction in that this anchorage, which extends transversely of the machine, has points of attachment for the springs, indicated by holes 17, that are arranged in a 100 horizontal plane and in concave curved relation with respect to a vertical plane passing transversely through the type bar segment to

thereby equalize the tension on the springs: or, defining the anchorage with relation to a vertical plane passing transversely of the machine through the rear frame 18 thereof, it will be seen that the points of attachment

17 for the springs are arranged from the center toward each end of member 15 at a progressively increasing distance with respect to the plane of the rear wall.

10 In Fig. 3 is shown a modified form of the invention. Here draw link 9 is provided with an integral looped portion 18 intermediate its ends and universal bar link 13 is hooked into the lower part of the loop while 15 the type bar operating spring is secured in the upper part of the loop.

In both Figs. 1 and 3, it will be observed, 20 the type bar operating spring is connected at a fixed point in the train of connections, 25 the compensation for inequality of extension of the springs being obtained by curved anchorage 15.

As is usual, in machines of this character, 25 member 15 may be mounted to rock on center 19 and is adjustable toward and away from the type segment by means of screw 20.

We claim:

1. A type bar action for typewriting machines comprising: a curved type bar segment, a series of type bars pivotally supported in the segment, a series of key levers, a universal bar, a series of intermediate connections between the type bars, key levers and the universal bar, a series of type bar operating springs, one for each type bar, each spring connected at a fixed point in the train of connections composed of the type bars, key levers, universal bar and intermediate connections, and an anchorage for said springs, extending transversely of the machine, the points of attachment for the springs, on said anchorage being arranged in a horizontal plane and in concave curved relation with respect to a vertical plane passing transversely through the type bar segment to thereby equalize the tension on the springs.

2. A type bar action for typewriting machines comprising: a curved type bar segment, a series of type bars pivotally supported in the segment, a series of key levers, a universal bar, a series of intermediate connections between the type bars, key levers and the universal bar, a series of type bar operating springs, one for each type bar, each spring connected at a fixed point in the train of connections composed of the type bars, key levers, universal bar and intermediate connections, an anchorage for said springs, extending transversely of the machine, the points of attachment for the springs on said anchorage being arranged in a horizontal plane and in concave curved relation with respect to a vertical

plane passing transversely through the type bar segment to thereby equalize the tension on the springs, and means for adjusting the anchorage toward and away from the type bar segment.

3. A type bar action for typewriting machines comprising: a curved type bar segment, a series of type bars pivotally supported in the segment, a series of key levers, a universal bar, a series of intermediate connections between the type bars, key levers, and the universal bar, one of said connections in each series consisting of a link having an integral looped portion intermediate its ends, a series of type bar operating springs, one for each type bar, each spring connected to the looped portion of a link, and an anchorage for said springs, extending transversely of the machine, the points of attachment for the springs on said anchorage being arranged in a horizontal plane and in concave curved relation with respect to a vertical plane passing transversely through the type bar segment to thereby equalize the tension on the springs.

4. A type bar action for typewriting machines comprising: a transversely extending and vertically curved type bar segment, a series of forwardly recumbent type bars pivotally supported in said segment, a series of key levers, a universal bar, a series of intermediate connections between the type bars, key levers and the universal bar, a series of type bar operating springs, one for each type bar, each spring connected at a fixed point in the train of connections composed of the type bars, key levers, universal bar and intermediate connections, and an anchorage for said springs, extending transversely of the machine, the points of attachment for the springs on said anchorage being arranged in a horizontal plane and in concave curved relation with respect to a vertical plane passing transversely through the type bar segment to thereby equalize the tension on the springs.

5. A type bar action for typewriting machines comprising: a transversely extending and vertically curved type bar segment, a series of forwardly recumbent type bars pivotally supported in said segment, a series of key levers, a universal bar, a series of intermediate connections between the type bars, key levers and the universal bar, one of said connections in each series consisting of a link having an integral looped portion intermediate its ends, a series of type bar operating springs, one for each type bar, each spring connected to the looped portion of a link, and an anchorage for said springs, extending transversely of the machine, the points of attachment for the springs on said anchorage being arranged in a horizontal plane and in concave curved relation with respect to a vertical plane passing trans-

versely through the type bar segment to thereby equalize the tension on the springs.

6. A type bar action for typewriting machines comprising: a curved type bar segment, a series of type bars pivotally supported in the segment, a series of key levers, intermediate connections for actuating the type bars from the key levers, a universal bar, a series of universal bar links between the universal bar and the train of connections including the key levers and the type bars, a series of type bar operating springs, one spring surrounding each link, and an anchorage for said springs, extending transversely of the machine, the points of attachment for the springs being arranged in a horizontal plane and in concave curved relation with respect to a vertical plane passing transversely through the type bar segment to thereby equalize the tension on the springs.

7. A type bar action for typewriting machines comprising: a transversely extending and vertically curved type bar segment, a series of forwardly recumbent type bars pivotally supported in said segment, a series of key levers, intermediate connections for actuating the type bars from the key levers,

a universal bar, a series of universal bar links between the universal bar and the train of connections including the key levers and the type bars, a series of type bar operating springs, one spring surrounding each link, and an anchorage for said springs, extending transversely of the machine, the points of attachment for the springs being arranged in a horizontal plane and in concave curved relation with respect to a vertical plane passing transversely through the type bar segment to thereby equalize the tension on the springs. 30 35

8. An anchorage for type bar operating springs consisting of a member extending transversely of the machine the points of attachment thereto for the springs being arranged, from the center toward each end of said member, at a progressively increasing distance with respect to a vertical plane passing transversely of the machine through the rear frame thereof.

Signed at Hartford in the county of Hartford and State of Connecticut this 26 day of June, 1922.

BERNARD J. DOWD.
ANTHONY UTZ.
